UNITED STATES PATENT OFFICE.

EDWARD C. ABEL, OF NEW YORK, N. Y.

DESIGN FOR A BROOCH OR SIMILAR ARTICLE.

SPECIFICATION forming part of Design No. 36,987, dated June 21, 1904.

Application filed May 6, 1904. Serial No. 206,765. Term of patent 3½ years.

To all whom it may concern:

Be it known that I, EDWARD C. ABEL, a citizen of the United States, residing in borough of Brooklyn, county of Kings, city and State of New York, have invented a new and original and ornamental Design for Brooches or Similar Articles, illustrated in the accompanying drawings, forming part thereof.

Figure 1 is a face view, and Fig. 2 an approximately central sectional view.

What I claim as new, and desire to secure by Letters Patent, is—

The ornamental design for a brooch or similar article substantially as herein shown.

EDWARD C. ABEL.
